[57] CLAIM

The ornamental design of a housing for a musical instrument, as shown and described.

DESCRIPTION

FIG. 1 is a front perspective view of a housing for musical instrument showing my new design;

FIG. 2 is a top plan view thereof;

FIG. 3 is a left side elevational view, the right side elevational view being substantially a mirror image of the side shown; and

FIG. 4 is a rear elevational view thereof.

The broken-line showing of keys, control buttons and pedals is for illustrative purposes only and forms no part of the claimed design.

FIG. 1
